DESK MEMORANDUM DEVICE

Filed Feb. 15, 1927

INVENTOR.
George R. Randolph
BY
Attorney.

UNITED STATES PATENT OFFICE

GUY P. RANDOLPH, OF PASADENA, CALIFORNIA, ASSIGNOR TO W. O. THOMPSON, OF PASADENA, CALIFORNIA

DESK MEMORANDUM DEVICE

Application filed February 15, 1927. Serial No. 168,299.

My invention relates to desk memorandum devices of the type containing a roll of paper to be used for memoranda purposes and then torn or cut from the roll, and it has among its objects to provide such a device in which the end of the paper is so directed through the device and exposed for receiving the memoranda that the commencement of the memoranda is toward the end of the paper and its continuance is toward the source or roll, thereby making it possible to continue the memoranda to any extent, or to follow one memorandum after another continuously in order toward the source from which the paper comes, instead of writing the memoranda by commencing at a distance from the end and writing toward the end of the paper to be torn from the supply, thus making it necessary if there is not room, to tear off the end of the paper and make a second piece.

Another object of my invention is to provide a combination guide and support for the part of the paper to be written upon, said combination guide and support also constituting a hinged cover for a container into which memoranda and pencils can be conveniently placed, in an out-of-sight place.

Other objects and advantages will be apparent from the following description of one practical embodiment of my invention, taken in connection with the accompanying sheet of drawing, in which:

Figure 1 is a perspective view of a device embodying my invention;

Figure 2 is a longitudinal, vertical sectional view on the position of line 2—2 of Fig. 3; and

Figure 3 is a view from line 3—3, Fig. 2, with the top part of the cover raised.

The body of the device is of box-like form, designated 4, with the rear slightly higher than the front in order to give a tapering top, hereinafter referred to. The body is preferably formed from sheet metal with the sides, 5, 5, between which is rotatably mounted a roll of paper, P, said sides tapering toward the front with a comparatively narrow front or end wall, 6. The rear end wall, designated 7, is shown to be a leaf like part of the metal turned upwardly with the corner spaces or

slots, 8, 8, and I have illustrated how a combination cover for the roll of paper, calendar holder and pencil holder can be detachably set into these slots, 8, 8. This member is designated 9, and at its opposite side are two rolls, as 10, forming pencil holders, the further one, Fig. 2, having shown therein a tall flexible staff, 11, with pencil cord, 12, and pencil attached thereto. In Fig. 1, a pen 11' is shown in the further roll (not seen). The body of said member 9, is curved over the roll of paper, P, and downwardly over the front thereof, with its edges folded in to form a calendar holding pocket, 9a. The bottom of said box or container is designated 4a, and directly under the roll of paper P, said bottom has a struck in leaf portion, 4b, forming a rear wall for the front part of said box, to provide a compartment to receive memoranda, pencils and the like, as may be desired. Said box is also provided with rubber feet, 13, 13.

A combination cover and guide or platen for the paper is hingedly connected at its upper end between the opposite sides and I will now describe this member. It is formed in the present showing of two thin metal channel-like members, 14, 15, the flanges of one overlapping or telescoping with the flanges of the other when the parts are put together. A hinge pin, 16, is put through the side members, 5, 5, and the upper ends of the overlapping flanges of said members, 14, 15. The inner channel member is provided at its lower end with a connecting pin, 17, and a roller 18, thereon, and the upper channel member is provided with a transverse slot, 19, therethrough near its lower end, and with a similar slot, 20, near its upper end, while the upper end is also provided with an extension lip, 21, bent slightly upwardly and forming a tearing edge on which to tear the paper from the body thereof. The strip of paper, p, from the roll P, is threaded downwardly between the members 14, 15, around the roller, 18, at the lower end of said cover member, and upwardly through the transverse slot, 19, over the top surface of the member 14, and thence through the transverse slot, 20, at the upper end of said member, 14, and up-

wardly behind, or under the lip extension, 21. It will be noted that the pivot pin 16 and the roller 18 are arranged in parallel relation with respect to each other, at opposite ends 5 of the platen member, so that said pin 16 will lie within the return loop formed in the strip of paper ρ , thereby permitting free tilting movement of the platen member without bringing undue strain upon that portion of 10 the paper extending between the roll P and the roller 18. It will also be observed that the bottom wall of the member 15 of the platen cooperates with the roller 18 to hold the lower portion of the return loop raised 15 free from the bottom of the chamber. A light spring wire, 22, is coiled around the hinge pin, 16, between said channel members, 14, 15, with its ends bearing upwardly against the underside of the top member, 14, and its 20 loop portion, 22a, resting upwardly against the underside of the extension lip, 21, and serving to hold the end of the paper up close to the said lip, whereby it can be readily grasped between the thumb and finger to be 25 pulled upwardly, as indicated in Fig. 2, ready to be torn along the top edge of the lip 21. The upper and lower ends of the under member, 15, are turned under slightly, as at 15a, 15a, see light broken line position, Fig. 1, 30 and a card, 23, can be placed therein, to receive telephone numbers, or other data frequently referred to. It is only necessary to raise the cover member, as shown in said light broken line position, to see said card.

35 It will be seen from the foregoing description and illustration of the invention that the paper passes downwardly through the cover member, or under the top portion thereof, around the roller 18, in the lower end of said 40 cover member, and thence upwardly through the slot, 19, and over the top surface of the top member, 14, which is smooth and forms a very efficient writing base for said paper, the upper end of said paper passing through the 45 transverse slot, 20, and up behind the lip extension, 21, at which it can be torn off as pulled through to any length desired. It will be noted that the writing on said paper is 50 toward the source from which the paper comes and that length of memorandum can be written without coming to the end of the paper, unless the entire roll, P, be used up. This is a very important feature of my invention. Under the cover member, within the 55 box, can be placed the various memoranda, taken for the owner of the device when he returns, or when he wishes to refer to them. The combination pencil holder and roll cover and calendar holder, designated 9, 9a, is easily 60 detachable, being slipped down into the slots, 8, 8, in front of the upturned leaf portion, 7, of the body.

65 We are aware that changes in details can be made in the invention without departing from the spirit thereof, and do not limit the

invention to the showing made for illustrative purposes, except as we may be limited by the hereto appended claims.

I claim:

1. A desk memorandum device including 70 a box structure, a cover and paper guide hingedly connected thereto at one end, its other end being free to be lifted to uncover a part of said box, said cover and paper guide consisting of two channel members placed together flatwise in telescoping relationship, 75 means for threading the end of a strip of paper through said members and around upwardly over the top surface of the top member, to receive writing thereupon, said top member having a tearing lip at its upper end and a slot in front thereof, whereby said paper passes through said slot and under said tearing lip to be torn along said lip, in 80 the manner indicated. 85

2. A continuous feed memorandum device including in combination a box structure having its two opposite sides of tapering form, 90 means for holding a roll of paper between said sides at their deeper ends, a combination cover and paper guide pivotally supported at its upper end between said opposite sides, the lower end of said cover and guide being adapted to be raised to give access to said box structure, said combination cover and 95 paper guide having a longitudinal passageway for said paper, guiding means at both ends of said cover and guide to permit feeding of said paper over said cover and guide and away from said lower end, and a tearing member at the upper top end of said guide under which said strip of paper passes, whereby said paper can be torn along said tearing member. 100

3. In a device of the character referred to, 105 a structure having two opposite sides forming a space therebetween, means for supporting a roll of paper between said sides, a pivoted member pivotally supported between said sides at its upper end and inclined downwardly to the end of said device, said pivoted member forming a cover and paper guide and adapted to be raised at its lower end to give access to the space between said sides and under said pivoted member, 110 said pivoted member having means for guiding paper therethrough above its bottom and within said member and around its lower end and upwardly over its top surface, and a tearing lip at the upper pivoted end of 115 said pivoted member under which said strip of paper passes, whereby the end of a strip of paper can be continuously pulled upwardly under said tearing lip and torn at any 120 length. 125

4. A device of the character referred to comprising a box structure of sheet metal having bottom and opposite upstanding sides of tapering form, means for holding a roll of paper between said opposite sides, a cover 130

member pivotally connected at its upper end between said sides in front of the position for said roll of paper, said cover member extending downwardly over the tapering space between said sides, said cover member having means for threading a strip of paper therethrough lengthwise thereof above the bottom thereof and upwardly over the top thereof, the top of said cover member serving as a writing support, and a tearing lip across the upper pivoted end of said cover member with space thereunder for said paper to pass.

5. A memorandum device comprising side walls, a paper guide and support member including two spaced plates pivotally mounted between the side walls, means for rotatably supporting a supply roll of paper adjacent the pivots of the guide and support member, and a guide roller on said member at its free end, whereby the paper may be led from the supply roller, through the channel formed by the spaced plates, and turned over the guide roller in the reverse direction.

6. A desk memorandum device comprising a box-like body, means at one end of said body for supporting a roll of paper, a platen having one end pivotally engaging the sides 25 of said body at a position between the roll-supporting means and the other end of said body, and means carried by the other end of said platen for engaging the paper so as to form a return loop therein, said platen also 30 having other means for guiding the return portion of said loop over the top of the platen.

7. A desk memorandum device comprising a box-like body, means at one end of said body for supporting a roll of paper, a platen 40 having side walls, pivot means movably connecting the side walls of said platen at one end to the sides of said body at a position between the roll-supporting means and the other end of the body, and means carried by 45 the other end of said platen for engaging the paper so as to form a return loop therein, said platen also having other means for guiding the return portion of said loop over the top of the platen.

50. 8. A desk memorandum device comprising a box-like body having a partition wall dividing said body into two compartments, means for supporting a roll of paper in one of said compartments, a platen for covering the 55 other compartment, means for pivotally supporting one end of the platen adjacent to said wall, and means carried by the other end of said platen for engaging the paper so as to form a return loop therein, said platen 60 also having other means for guiding the return portion of said loop over the top of the platen.

65. 9. A desk memorandum device comprising a body having side walls, a platen also having side walls, means pivotally connecting the

side walls of said platen at one end with the side walls of said body, so that the platen will lie between said body walls, and means carried by the other end of said platen for engaging the paper so as to form a return loop 70 therein, said platen also having other means for guiding the return portion of said loop over the top of the platen.

10. A desk memorandum device comprising a box-like body, means at one end of said body for supporting a roll of paper, a platen having one end pivotally engaging the sides of said body at a position between the roll-supporting means and the other end of said body, means carried by the other end of said platen for engaging the paper so as to form a return loop therein, said platen also having other means for guiding the return portion of said loop over the top of the platen, and means for holding the lower portion of said return loop free from the bottom of said box-like body.

15. 11. A desk memorandum device comprising a box-like body, means at one end of said body for supporting a roll of paper, a hollow platen provided with top and bottom walls, and having one end pivotally engaging the sides of said body, and means carried by the other end of said platen for engaging the paper so as to form a return loop therein, the 90 top wall of said platen having other means for guiding the return portion of said loop over the top of the platen, the bottom wall of said platen holding the lower portion of said return loop free from the bottom of said 95 box-like body.

20. 12. A desk memorandum device comprising a hollow body having means for supporting a supply of writing material, a platen having a pivot at one end engaging said hollow body, the other end being free, so that the platen may be tilted, said platen carrying means at its free end for engaging a portion of said writing material so as to form a return loop, and other means in its top for 105 guiding the return portion of said loop, said pivot and said loop-forming means being in parallel relation with respect to each other at opposite ends of the platen, so that the pivot will lie in a plane within said loop.

25. 13. A desk memorandum device comprising a hollow body, a cover for said body pivoted thereto at one end, the other end being free so that said cover may be tilted, said cover having a platen portion, and a 110 roller mounted in the free end of said cover beneath said platen, so that a return loop of writing material may be formed around the roller, said platen having means for guiding the return portion of said loop over the 115 top of the platen, said roller and said pivot being in parallel relation with respect to each other at opposite ends of the platen, so that the pivot will lie in a plane within said loop.

30. 14. A device of the character described 120

comprising a hollow frame adapted to support a roll of paper in one end thereof, a tiltable writing plate covering the other end of the frame and forming a chamber therewith, a roller carried by the lower end of the plate over which paper is passed from the roll and to the upper surface of the plate.

15. A device of the character described comprising a hollow frame adapted to support a roll of paper in one end thereof, a tiltable writing plate covering the other end of the frame and forming a chamber therewith, a roller at one end of the plate over which paper is passed from the roll and to the upper surface of the plate, and means for holding the run of paper from the roll to the roller raised free from the chamber.

Signed at Los Angeles, Los Angeles County, California, this 8th day of February, 1927.
